COLLAPSIBLE CONTAINER

William T. Mooney, Cleveland, Ohio, assignor to
James O. Evans, Cleveland, Ohio

Application August 16, 1935, Serial No. 36,525

8 Claims. (Cl. 220—5)

The present application is a continuation in part of application Serial No. 574,715, filed November 13, 1931.

My invention relates, in general, to collapsible containers and more particularly to a collapsible barrel being made up of sections which interlock and covers for the same.

An object of my invention is to provide a container which may be shipped and packed in sections and assembled into a complete container when ready for use, and then collapsed into sections after used.

Another object of my invention is to provide a metal barrel which is composed of a plurality of arcuate sections which may be joined together by interlocking means to form the body of the barrel and covers which will fit over the ends of the body of the barrel.

A further object of my invention is to provide a cylinder shaped container having a cover which threadably engages the body of the container and which locks against disengagement by projecting bosses and complementary recesses.

Another object of my invention is to provide a cylinder shaped container having spirally mounted ribs interrupted into sections so that one section forms a projection in line with the other section of the rib, the ribs being mounted near the end of the body of the cylinder and a cover having complementary grooves interrupted into two sections so that one section forms a recess in alignment with the other section of the groove and complementing the projection on the cylinder, that the cover may be threadably engaged upon the cylinder and automatically locked thereon by turning the cover to the extent that the projection or bosses on the cylinder engage in the recesses or short sections of grooves in the cover.

A still further object of my invention is to provide a cover for a cylindrical container which has means projecting from the cover for engaging a wrench for the purpose of screwing the cover on to the body of the container.

Another object of my invention is to provide a plurality of arcuate container sections which may be engaged along their longitudinal edge by slidably engaging the complementary edges together and so that the resulting joint does not project outside the circumference of the container to prevent the rolling of the container in use.

A still further object is to provide a joint for the arcuate sections of a cylindrical container which comprises a male section and a comple-

mentary female section which is engaged by longitudinally sliding the male section into the female section so as to provide against their disengagement in a circumferential direction.

Other objects and a fuller understanding of my invention may be had by referring to the following description and claims, together with the accompanying drawing, in which:

Figure 1 represents a side view of my container with the arcuate sections joined and the bottom cover screwed in place upon the body of the container.

Figure 2 represents a side view of the top cover, not yet threaded upon the top of the container as shown in Figure 1. The end covers, as shown in Figure 2, and the end cover engaged in place on the cylinder in Figure 1, are similar.

Figure 3 represents a cross-sectional view through the line 3—3 of Figure 1.

Figure 4 is a cross-sectional view of the top of the container with the cover in place, together with the wrench used for screwing the cover on the container, and

Figure 5 represents a plan view of the top of the cover shown in Figure 2 with a part of the wrench shown.

In my illustration shown in Figure 1, the body of the container, is composed of section 1 and section 2. The illustration shown in Figure 1 shows only one side of the container in which there are two arcuate sections, section 1 and section 2. Therefore, there is only one joint 19 shown by the section 1 and section 2. The arcuate sections illustrated are semi-cylindrical but it is to be understood that my invention includes the use of arcuate sections of any size so that the total number of sections complete a cylinder.

Details of the joint taken along the line 3—3 of Figure 1 are shown in Figure 3, but at this point it can be said that the section 1 and section 2 are joined by raising one section so that the complementary sections are above one another and then slidably engaged one with the other. In this manner section 1 and section 2 are engaged against circumferential stress, though they may be moved relative to each other in a longitudinal direction.

The ends of the body sections are beaded around the wire 25 to form the beaded edge 20. In this manner the beaded edges of the sections form a substantially rigid and strong portion of the sections. Mounted upon the outside surface of the sections near the ends thereof, are the threaded ribs. Upon section 1, there is shown

a portion of a rib 15 and a rib 16 which is interrupted to again appear as the short rib or boss 17 and the short rib or boss 18. These short ribs 17 and 18 are in alignment with the principal portion of the ribs 15 and 16, the short rib 17 being in alignment with the rib 15 and the short rib being in alignment with the rib 16. Upon the upper end of section 2 is shown a rib 13 and a rib 14. The short ribs or bosses associated with these ribs are upon the other side of the container illustrated in Figure 1, and therefore, are not shown. Mounted upon the bottom end of the container illustrated in Figure 1 is the end cover 4. Shown upon the end cover 4 in Figure 1 is the spiral groove 5 and the spiral groove 6. These grooves are interrupted to form a separate short groove or recess 9 and a separate short groove or recess 10. The short groove 9 is in alignment with the groove 5 and the short groove 10 is in alignment with the groove 6. There is also shown a groove 7 and a groove 8 spirally mounted upon the cover 4. The corresponding short grooves or recesses in alignment with the grooves 7 and 8 are upon the other side of the illustrated container and therefore, are not shown in Figure 1.

Since the end covers 4 are the same for both ends of the container, the method of mounting the cover upon the joined sections will be discussed in a later place.

Figure 1 shows the end cover mounted upon the bottom end of the container and shows its appearance after being completely mounted.

Figure 2 shows the end cover 4 detached from the container walls and shows, in some detail, the construction of the end cover 4. Spirally mounted upon the end cover 4 are two parallel grooves 7 and 8 which are interrupted to form short grooves or recesses 11 and 12. The short groove 11 is in alignment with groove 7 and the short groove 12 is in alignment with groove 8. The short grooves 11 and 12 are upon the other side of the cover 4 and therefore, are shown in dotted lines. Also spirally mounted upon the cover 4 are grooves 5 and 6 which are interrupted to form the short grooves or recesses 9 and 10.

The edge of the container is cut away in such fashion so that the cover 4 may fit down over the container and the grooves 7 and 8 engage with, and slide over, the ribs 15 and 16, and the short ribs 17 and 18 of the section 1 of the container. The edge of the cover 4 is also cut away on the farther side so that the ribs 5 and 6 of the cover 4 are engaged, with, and slide along, the ribs 13 and 14 of section 2 of the container. In this way, the cover 4 may be placed over the container and the corresponding grooves and recesses in proper place for engagement by turning the cover in a clockwise direction upon the container.

The top of the cover 4 is depressed in a manner to form the sunken surface 23 of the cover 4 and to leave an outside peripheral edge 24. Raised above the level of the sunken surface 23 are two projecting portions 21 and 22. The functions of these projections 21 and 22 are for the purpose of providing means to engage a wrench 27 and turning the cover 4 upon the container as shown in Figure 4.

The purpose of the short ribs which, as shown in Figure 1 as 17 and 18 and the short groove 11 and 12, is to lock the cover 4 upon the container. This is done by turning the cover 4 until the interruption between the groove 7 and the short groove 11 comes in contact with the

short rib 17, or until the interruption between the groove 8 and the short groove 12 comes in contact with the short rib 18. At this point, the cover would be unable to be threaded upon the container to a final point except for the fact that the wall of the cover 4 slightly gives in an outward direction and the wall of the section 1 slightly gives in an inner direction. Thus, by continued turning, the short ribs 17 and 18 slide beyond the interruptions between the grooves 7 and 8 and the short grooves 11 and 12 until the short ribs 17 and 18 snap into, and fill the short grooves 11 and 12.

In a similar way the ribs 13 and 14 engage with grooves 5 and 6 until the short ribs (not shown in Figure 1) which are in alignment with ribs 13 and 14, come in contact with the interruptions between the grooves 5 and 6 and the short grooves 9 and 10. In a similar way, the cover 4 is turned until the short ribs (not shown in Figure 1) which are in alignment with the ribs 13 and 14, are forced past the interruptions in the grooves 5 and 6 until the short ribs snap into, and fill the short grooves 9 and 10. It is thus to be seen that the cover 4 is securely locked upon the container made up of sections 1 and 2 in a manner that the cover 4 may not be disengaged from the container except by forcing the short ribs past the interruptions of the grooves in a reverse manner from that described above. Needing considerable force, a wrench is necessary to turn the cover on or off past these interlocking portions. The device acts an an efficient interlocking means for keeping the cover upon the container.

Figure 4 is a cross sectional view of the top of the container composed of sections 1 and 2 and a cross sectional view of the cover 4 in place over the top of the container. As the container is cut away, we look into the side of the container from the inside, thus showing the back of the spiral ribs from within the container. In this view, the groove 6 is slidably engaged with rib 16 and groove 5 is slidably engaged with the rib 15, while groove 8 is slidably engaged with the rib 14 and groove 7 is slidably engaged with the rib 13. The only short rib shown in Figure 4 is the short rib 26 which engages with, and fits into, the short groove 12 of Figure 2. Figure 4 illustrates the method of turning the cover down upon the container in which the wrench 27 is bent downward at point 28 and straight against the point 29 so as to fit down into the sunken top surface 23 of the cover 4. The wrench 27 has in it holes 20 and 31 which respectively fit over the projections 21 and 22 of the cover 4. The outside edge of the cover 4 is shown as edge 24. The cross sectional view of figure 4 also shows the wire 25 over which the beaded edge 20 of section 2 of the container is formed.

Figure 5 is a plan view of the top of the cover 4, showing the groove 5 and the short groove 9 in alignment therewith, and the groove 7 with the short groove 11 in alignment therewith. The top of the edge 24 is shown surrounding the sunken surface 23. A part of the wrench 27 is shown with its two holes 30 and 31 which are fitted over the projections 21 and 22.

Figure 3 shows in detail, the construction of the joint between sections 1 and 2 which is a cross section between the line 3-3 of Figure 1. The male portion along the longitudinal edge of section 1 is formed by bending the metal of section 1 inward towards the radial center of the container at point 19 for a short distance

5 to point 32; thence substantially parallel with the circumference of the container to point 33, from whence it is bent back parallel to the circumference of the container by leaving a space for the fitting of the female portion of section 2. This male portion of section 1 is again bent at point 34 back upon itself and runs again parallel to the circumference of the container approximately to the point 35 where it is again bent back upon itself to end at point 33.

10 The female portion of section 2 is formed by bending inward towards the radial center of the container at point 19 to approximately a point 32 whence it is bent parallel to the circumference of the container towards point 36 whence it is bent back upon itself around back to point 34, whence it is again bent back upon itself parallel to the circumference of the container to point 35 and again bent inward towards 15 the radial center of the container in a looped fashion and back to terminate at approximately to point 33.

15 In this manner, the male portion of section 1 is firmly engaged within the female portion of section 2 in such a way as to resist disengagement in a circumferential direction. The male portion of section 1 is engaged with the female portion of section 2 by placing the joint portion of one section over the joint portion of the other 20 section and introducing the male portion of section 1 into the female portion of section 2 and then sliding the male portion in a longitudinal direction into the female portion of section 2. Thus, the two sections 1 and 2 are locked together and can only become interlocked by moving the sections in a longitudinal direction parallel to each other. The male portion of section 1 and the female portion of section 2 both project 25 so as to be within the outside circumference of the container after the sections 1 and 2 are assembled. In this way there is no obstacle or hindrance to the rolling of the barrel as the joint between the sections is free from any obstruction upon the outside of the joint.

30 35 40 45 Each section of the container has a male portion upon one longitudinal edge and a complementary female portion upon its other longitudinal edge, so that each section may easily be joined to its adjoining section, each female portion being adjacent to the male portion of the adjacent section. While in the illustrated case there are only two sections to the container body, my invention includes the use of any number of arcuate sections which will complete a cylinder 50 and each of these sections will have one longitudinal edge having a male portion and the other longitudinal edge having a complementary female portion.

45 50 55 60 65 70 75 In practice, I prefer to use metal for my container as it is easily shaped for the purpose explained herein, although other materials may be used. In the use of my invention, the arcuate sections may be made of sheet metal and formed in the usual manner preferably by having the ribs formed in the side of the arcuate sections. These arcuate sections may be made in quantity, packed and shipped in an unassembled condition, thus taking very little storage and shipping space. The two end covers are similar to each other and likewise are made of sheet metal. These, too, are easily stored or shipped in an unassembled condition. In this manner, the parts of my container or barrel can be stored and transported in a very small space and when ready for use may be assembled in the manner heretofore described.

After the container has been used, it may be taken apart and stored in a relatively small space until ready for use again. The container which I have invented is not only economical and convenient in itself, but it is economical and convenient to store and to transport.

5 10 15 20 25 Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

15 20 25 30 35 40 45 50 55 60 65 70 75 1. A cylinder shaped container comprising a body portion made up of sections, one longitudinal edge of each section being provided with a male portion projecting toward the radial center of said container, said male portion having an enlarged head and a relatively narrow neck, the other longitudinal edge of said each section being provided with a complementary female portion projecting toward the radial center of said container, said female portion having an enlarged inner recess and a relatively narrow throat of smaller dimensions than the enlarged end of the said male portion, the lateral dimensions of said recess being radial of said container, the said male portion and the said female portion being formed by folding the respective longitudinal edges, the arrangement of the said male portion and the said female portion being such that the sections are joined together by sliding in a longitudinal direction the male portion of each section into the female portion of the adjacent section to form the said body portion, thereby locking the sections together against disengagement in a circumferential direction, and two end covers adapted to threadably engage the assembled sections so that said sections are restrained against disengagement in a longitudinal direction.

2. A barrel shaped container comprising a plurality of similar arcuate sections and two end covers, each of said sections having longitudinal edges, one of said edges having a hook portion disposed in one direction and the other of said edges having a complementary hook portion disposed in the opposite direction, the lateral dimensions of said hook portions being radial of said container, the two said hook portions being adapted to engage with the hook portions on the adjoining sections so as to resist disengagement of the assembled sections in a circumferential direction, one of the engaging hook portions being extended substantially the length of said each arcuate section so that said hook portions may be placed end to end and slidably engaged in a longitudinal direction, the joined hook portions being disposed substantially below the outside circumferential surface of the container so as to permit rolling of the container, and the two end covers being adapted to threadably engage the assembled sections so that said sections are restrained against disengagement in a longitudinal direction.

3. A cylinder shaped container having a body and end covers, the said body and the said end covers having a complementary spiral rib and recess for threadably engaging the said end covers over the ends of the body, the said spiral rib and recess being interrupted into two separate portions each by a third portion extending between the two said portions, said third portion being on the same cylindrical surface as the

5 adjacent other parts of said body and said cover, said two separate portions being of unequal length, the shorter of said unequal portions being positioned nearer the ends of said container than the longer of said unequal portions and being adapted to interlock at said portions nearer the ends of the said container than the longer of the unequal portions, the combination of the body and the end covers being such that the 10 covers may be threaded on the respective ends of the body and forcibly threaded over and past the interruptions in the ribs and recesses, thus holding the covers on the body so as to resist disengagement.

15 4. A cylindrical sheet metal barrel or container comprising arcuate portions provided with interlocking sunken joints longitudinally slidable upon each other, one of said interlocking sunken joints being extended substantially the length of said 20 arcuate sections so that said sunken joints may be placed end to end and slidably engaged in a longitudinal direction, and a cover and base therefor for holding said portions against disengagement in a longitudinal direction, said base 25 and cover and the arcuate portions being provided with complementary spiral ribs and grooves, and automatically interlocking means in alignment with said spiral ribs and grooves for holding the base and cover on the assembled 30 portions, said automatic interlocking means being separate, and at a distance, from said ribs and grooves.

5. A cylindrical sheet metal barrel or container comprising arcuate portions provided with interlocking sunken joints longitudinally slidable upon each other, and a cover and base therefor for holding said portions against disengagement in a longitudinal direction, said base and cover and the arcuate portions being provided with 35 complementary spiral ribs and grooves, and automatically interlocking means in alignment with said spiral ribs and grooves for holding the base and cover on the assembled arcuate portions, said interlocking means being separate, and at 40 a distance, from said ribs and grooves and being positioned nearer the ends of said container than the said ribs and grooves, said spiral ribs and grooves at the opposite ends of said container having flat lateral sides opposed to each other.

50 6. In a cylindrical barrel or container, a body and a detachable base and cover therefor, said body being composed of a plurality of arcuate sections engageable along their longitudinal edges by longitudinally sliding said sections together 55 to form said body, said body being provided with spaced groups of spiral ribs at each end thereof,

said base and cover being provided with complementary groups of spiral grooves, said groups at each end being positioned at different levels to permit successive engagement of the groups of ribs and grooves at different levels, and automatically interlocking bosses and recesses in spiral alignment with said ribs and grooves, said bosses and recesses being separate, and at a distance, from said ribs and grooves and being positioned nearer the end of said container than 10 the said ribs and grooves.

7. A collapsible barrel, in combination, a body composed of arcuate substantially similar sections, one vertical edge of each section being provided with a flattened T shaped male portion 15 formed by crimping said edge back upon itself and the opposite vertical edge being provided with a complementary female portion similarly formed from said edge, the edges of opposed sections being interlocked with each other, the 20 lateral dimension of said interlocked edges being disposed radially and inwardly of said barrel below the outer circumference of said barrel, one of the said portions being extended the length of said barrel so that the sections may be joined 25 together by placing the said portions in alignment and sliding them together in a longitudinal direction, and similarly constructed end members adapted to engage the ends of said sections for holding the said sections from longitudinal disengagement and for closing the ends of said 30 barrel.

8. A barrel shaped container comprising a body portion made up of sections, one longitudinal edge of each section being provided with a male portion which lies below the external surface of that portion of each of the sections adjacent to the said longitudinal edge, said male portion having an enlarged head and a relatively narrow neck and being formed by folding the said longitudinal edge, the other longitudinal edge of each section being provided with a complementary female portion for longitudinally receiving said male portion, said female portion having an enlarged inner recess and a relatively narrow longitudinal opening of smaller dimensions than the enlarged end of the said male portion, said longitudinal opening being disposed internally of the container, and being formed by folding the said edge, the arrangement of the said male portion and the said female portion being such that the sections are joined together to form said body portion, and are locked together against disengagement in a circumferential direction.

WILLIAM T. MOONEY.
